UNITED STATES PATENT OFFICE.

MASAYOSHI TAKEUCHI, OF SEATTLE, WASHINGTON.

DESIGN FOR AN INFANT'S BATH-COT.

56,036.

Specification for Design.

Patented Aug. 10, 1920.

Application filed October 4, 1919. Serial No. 328,601. Term of patent 14 years.

To all whom it may concern:

Be it known that I, MASAYOSHI TAKEUCHI, a subject of the Emperor of Japan, and residing at Seattle, in the county of King and State of Washington, have invented a new, original, and ornamental Design for an Infant's Bath-Cot, of which the following is a specification, reference being had to the accompanying drawing, forming part thereof.

The figure is a perspective view of an infant's bath cot.

I claim:

The ornamental design for an infant's bath cot, as shown.

MASAYOSHI TAKEUCHI.
